UNITED STATES PATENT OFFICE

113,804

DESIGN FOR A DRESS ENSEMBLE

Simon Etkin, New York, N. Y.

Application January 7, 1939, Serial No. 82,212

Term of patent 3½ years

To all whom it may concern:

Be it known that I, Simon Etkin, a citizen of the United States, residing at 230 West 38th Street, city of New York, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my design;

Fig. 2 is a rear view of the ensemble shown in Fig. 1;

Fig. 3 is a front view of the dress section of the ensemble shown in Fig. 1;

Fig. 4 is a rear view of Fig. 3; and

Fig. 5 is an enlarged fragmentary view of the dress portion illustrating the embroidered trim at the neck line.

I claim:

The ornamental design for a dress ensemble, substantially as shown and described.

SIMON ETKIN.
